UNITED STATES PATENT OFFICE

2,388,110

TOY HORSE

Neil F. Atherton, Wooddale, Ill., assignor to M. P. Heinz Machine Co., Chicago, Ill., a corporation of Illinois

Application July 9, 1945, Serial No. 603,975

9 Claims. (Cl. 272—52)

This invention relates to an improved toy horse, and has for one of its principal objects the provision of a toy horse in the shape of a hobby horse, which can be ridden by children, and which will, in addition to furnishing considerable amusement, also comprise a source of beneficial exercise.

One of the important objects of this invention is to provide in a toy horse a mechanical movement which will simulate to some extent the actions of a live horse when being ridden, and which furthermore can be adjusted so that these simulated actions may be controlled to accommodate children of various sizes and temperaments.

Another and further important object of the invention is to provide a simple, readily constructed and at the same time rugged device which will withstand considerable hard usage such as toys of this type encounter, and which, if broken, can be readily repaired.

Another and still further object of the invention is to provide in a toy horse means for rocking the same or producing a simulated galloping motion, and which at the same time will produce a noise somewhat simulating the neigh of a horse.

Other and further important objects of the invention will be apparent from the disclosures in the accompanying drawing and following specifications.

The invention, in a preferred form, is shown in the drawing and hereinafter more fully described.

In the drawing:

Figure 1 is a side elevation of the improved toy horse of this invention, showing a preferred embodiment of the invention.

Figure 2 is a bottom plan of the seat, showing in more detail the support therefor and the means whereby a bucking effect is simulated.

Figure 3 is a vertical section of the support of the structure, showing a portion of the element which connects the head and seat of the horse to this support.

Figure 4 is a partial sectional view taken on the line 4—4 of Figure 3, looking in the direction indicated by the arrows.

As shown in the drawing:

The reference numeral 10 indicates generally the base of the improved toy horse of this invention, and in the preferred embodiment this base comprises a longitudinal tube such as is best illustrated in Figure 3, of a desired length and supported at each end by transversely extending elements 12 and 14, which are preferably in the

form of metallic stampings, but which could be of some other material, if desired or convenient.

The ends of the tube 10 are fitted into bosses formed integral with the end pieces 12 and 14, as best shown in Figures 3 and 4, and the end elements 12 and 14 are provided with rubber cushions 16, so that the floor upon which the device is used will not be unduly marred. Casters may be provided, if desired, or the device may be mounted on wheels.

Fitted into the forward portion of the tubular element 10 is a longitudinally extending rod 18, which projects beyond the forward end of the tube, as illustrated, and which is surrounded by a helical spring 20, the helical spring being wholly contained within the tube and held in position with respect to the rod 18 by means of a plunger 22 at the inner end of the rod, which construction is surmounted by a nut 24. The spring 20 is of the compression type and the forward end operates against an adjusting nut 26, which is screw-threaded mounted in the corresponding portion of the supporting bracket 14. Turning of the screw threaded elements 26 will adjust the working compression of the spring 20.

The forward end of the rod 18 is screw threaded and upon this screw threaded end is mounted a pair of locking bolts 28, these being positioned beyond an upwardly extending strap element 30, shaped as shown in Figure 3. This strap element 30 has welded to or integral therewith a rearwardly extending boss or bosses 32, which have openings therein, these openings adapted to be aligned with corresponding openings in upwardly extending lugs 34 formed integral with the base element 13. Through these aligned openings a shaft 36 is passed, the same being held in position by a suitable nut 38.

Affixed to the upper inwardly extending nut of the element 30—32 by means of bolts and nuts 40, is a supporting element in the form of a metallic strap or the like 42, which is positioned at a normal angle of approximately 30 degrees to the tube 10 and upon the upper end of which is mounted the seat portion 44 and also the head portion 46, which simulates the neck and head of a horse. The bolts and nuts 40 are provided so that the device can be readily disassembled for crating and shipping. These can be eliminated if desired.

The outermost end of the supporting metallic strap 42 is turned inwardly at an angle so that it is approximately parallel with the tube 10, as shown at 48 in Figure 1, and to this portion is fastened, by means of suitable bolts and nuts,

a seat-supporting member 50, which is also preferably in the form of a metallic strap having its rear end bent into a loop, as shown at 52.

Surmounting the forward portion of the element 50 is a pair of lugs through which a pivot pin 54 passes, this pivot pin also passing through corresponding lugs forming part of a strap 56, which is fastened to the under face of the seat 44. This strap 56 is bent into a U-shaped loop at its forward end, as best shown in Figure 1, and the outer end of this U-shaped loop is adapted to contact the end of an adjustable bolt 58 which is mounted in a suitable screw threaded opening in the supporting metallic strap 42.

As best shown by the dot and dash lines in Figure 1, the pivoting of the seat at the point 54 enables the same to rock about this point. The rear end of the seat contacts the loop 52 of the metallic element 50 when the child sits thereupon. Any up and down motion of the structure will cause a rocking of the seat portion about the pivot 54; and this rocking can be controlled by positioning of the adjusting bolt 58. In this way the device can be adjusted for children of various ages and different degrees of timidity. A bolt 60 depends from the under face of the seat 44 through a slot in the strap element 50, whereby the structure is maintained in proper alignment, and this bolt 60 is also provided with an adjusting nut 62 to supplement the action of the adjusting bolt 58.

Another feature of the apparatus is the provision of a noise-making attachment which includes a packing element at the inner end of the rod 18, and which obviously moves to and fro in the tube 10 as the device is operated.

Positioned beyond the inner end of the rod 18 is a partition or stop 64 which closes the tube 10 at this point, and between this stop 64 and the piston element 22 is an opening 66 in the tube 10. This opening 66 is covered by means of a reed 68 held in position by a pin 70 so that air expelled through the opening 66 will produce a musical note as the child bobs up and down on the horse. This can be so constructed as to simulate the neigh of a horse.

A support for the child's feet is provided by means of a cross bar 72 mounted on the strap element 42 by means of suitable nut and bolt combination 74, and a handle to be grasped by the child's hands is provided fitted through the horse's neck and adjacent its head at a point 76.

It will be obvious that the compression spring 28 may be replaced by a tension spring, and that the stiffness of the element 42 can be varied to produce additional springiness if desired. It will further be obvious that the bucking action may be accomplished in various ways other than that set forth, and that the construction of the pivot points may be varied as desired or convenient. The actual material may also be changed and instead of a horse, other simulated animals may be employed.

I am aware that many changes may be made and numerous details of construction varied throughout a wide range without departing from the principles of this invention, and I, therefore, do not propose limiting the patent granted hereon otherwise than as necessitated by the prior art.

I claim as my invention:

1. A toy horse comprising a base element in the form of a tube, supporting legs therefor, a piston rod movable in the tube, a spring in the tube controlling the action of the piston, a seat and head combination for the horse, a supporting

member connecting the seat and head combination to the base, a pivot point for the supporting member adjacent the forward end of the base and a connection between the supporting member and the piston rod.

2. A toy horse comprising a base element in the form of a tube, supporting legs therefor, a piston rod movable in the tube, a spring in the tube controlling the action of the piston, a seat and head combination for the horse, a supporting member connecting the seat and head combination to the base, a pivot point for the supporting member adjacent the forward end of the base and a connection between the supporting member and the piston rod, this connection comprising a slot in the supporting member through which the forward end of the piston rod projects, and adjusting bolts on the forward end of the piston rod.

3. A toy horse comprising a base element in the form of a tube, supporting legs therefor, a piston rod movable in the tube, a spring in the tube controlling the action of the piston, a seat and head combination for the horse, a supporting member connecting the seat and head combination to the base, a pivot point for the supporting member adjacent the forward end of the base and a connection between the supporting member and the piston rod, and means for varying the compression of the spring.

4. A toy horse comprising a base element in the form of a tube, supporting legs therefor, a piston rod movable in the tube, a spring in the tube controlling the action of the piston, a seat and head combination for the horse, a supporting member connecting the seat and head combination to the base, a pivot point for the supporting member adjacent the forward end of the base and a connection between the supporting member and the piston rod, and a pivotal connection between the seat and its supporting element.

5. A toy horse comprising a base element in the form of a tube, supporting legs therefor, a piston rod movable in the tube, a spring in the tube controlling the action of the piston, a seat and head combination for the horse, a supporting member connecting the seat and head combination to the base, a pivot point for the supporting member adjacent the forward end of the base and a connection between the supporting member and the piston rod, and a pivotal connection between the seat and its supporting element whereby a bucking action is simulated.

6. A toy horse comprising a base element in the form of a tube, supporting legs therefor, a piston rod movable in the tube, a spring in the tube controlling the action of the piston, a seat and head combination for the horse, a supporting member connecting the seat and head combination to the base, a pivot point for the supporting member adjacent the forward end of the base and a connection between the supporting member and the piston rod, and a pivotal connection between the seat and its supporting element whereby a bucking action is simulated, and an adjustable stop mounted in the support for the seat whereby the amount of the bucking action is controlled.

7. A toy horse comprising a base element in the form of a tube, supporting legs therefor, a piston rod movable in the tube, a spring in the tube controlling the action of the piston, a seat and head combination for the horse, a supporting member connecting the seat and head combination to the base, a pivot point for the sup-

porting member adjacent the forward end of the base and a connection between the supporting member and the piston rod, and a pivotal connection between the seat and its supporting element whereby a bucking action is simulated, and an adjustable stop mounted in the support for the seat whereby the amount of the bucking action is controlled, and a further stop and adjusting means provided beneath the seat and adjacent the rear end of its support.

8. A toy horse comprising a base element in the form of a tube, supporting legs therefor, a piston rod movable in the tube, a spring in the tube controlling the action of the piston, a seat and head combination for the horse, a supporting member connecting the seat and head combination to the base, a pivot point for the supporting member adjacent the forward end of the base and a connection between the supporting member and the piston rod, and a pivotal connection between the seat and its supporting element whereby a bucking action is simulated, and

an adjustable stop mounted in the support for the seat whereby the amount of the bucking action is controlled, and a further stop and adjusting means provided beneath the seat and adjacent the rear end of its support, together with a support for the child's feet on the element which connects the head and seat portion to the base.

9. A toy horse comprising a base element in the form of a tube, supporting legs therefor, a piston rod movable in the tube, a spring in the tube controlling the action of the piston, a seat and head combination for the horse, a supporting member connecting the seat and head combination to the base, a pivot point for the supporting member adjacent the forward end of the base and a connection between the supporting member and the piston rod, a piston on the inner end of the rod in the tube, and an opening covered by a reed in the tube beyond the piston whereby a noise simulating the neigh of a horse is produced when the device is ridden.
